DESIGN FOR A COMBINED CRIB AND CABINET

George M. Robison, Sherwood, Mich.

Application October 10, 1941, Serial No. 103,711

Term of patent 7 years

To all whom it may concern:

Be it known that I, George M. Robison, a citizen of the United States, residing at Sherwood, in the county of Branch and State of Michigan, have invented a new, original, and ornamental Design for a Combined Crib and Cabinet, of which the following is a specification, reference being had to the accompanying drawing, forming a part thereof, and wherein:

I claim:

The ornamental design for a combined crib and cabinet, as shown.

GEORGE M. ROBISON.
